HEEL PIECE, PARTICULARLY OF HARD RUBBER WITH CELLULOID COATING

Friedrich Stübbe, Vlotho (Weser), Germany

Application November 23, 1953, Serial No. 393,870

6 Claims. (Cl. 36—35)

The instant invention relates to shoe heel lifts, particularly of hard rubber and having a layer of Celluloid at the attaching surface.

An object of the invention is to provide a lift of which the Celluloid layer will not chip off or cut at its edges into the covering of cloth or leather of the heel to which the lift is attached.

A further object of the invention is to provide a lift which, while retaining its spherical curvature imparted to it by the Celluloid layer on its attaching surface, eliminates the potential unsightliness with use of the heel to which it is attached caused by the wearing and cutting action of the Celluloid.

A further object of the invention is to provide a soft, non-brittle, cushioning layer on the attaching surface of the Celluloid layer of shoe lifts.

I accomplish the foregoing, and other, objects by providing the shoe lift having a Celluloid layer to impart a spherical curvature to the hard rubber body thereof with a soft protective, cushioning, layer over the Celluloid or the peripheral portions of the Celluloid. The covering layer is preferably of a non-brittle soft material and I have found such covering layers of fibrous material, leather, or rubber, of particular adaptability. The covering layer over the Celluloid serves two functions, namely to prevent chipping of the Celluloid layer as it develops cracks in use, and to prevent direct contact at the peripheral edges between the sharp edge of the Celluloid layer and the lower region of the cloth or leather covering of the heel to which the lift is attached, and thus to prevent cutting of the relatively soft material of such cloth or leather. The heel per se thus remains intact while by the time the edge of the Celluloid layer cuts the protective layer of the lift, the lift due to wear of its body will require renewal anyhow.

The invention will now be described in more detail in connection with various preferred embodiments and with reference to the accompanying drawings, in which:

Fig. 1 is a plan view of a heel lift according to the invention;

Fig. 2 is a view of the heel lift seen in the direction of arrow II of Fig. 1;

Fig. 3 is a sectional view taken along line III—III of Fig. 1;

Fig. 4 is a plan view, corresponding to Fig. 1, of a heel lift, the attachment of the cushioning layer being restricted to the peripheral zone of the lift, and

Fig. 5 is a plan view corresponding to Fig. 1 and showing a heel lift with welt-shaped cushioning layer.

Referring now to Figs. 1 to 3, the heel lift comprises a hard rubber member 1, to which is fixed a Celluloid layer 2. A cushioning layer 3 of soft material, for example of fibrous material, leather, or rubber, is attached to the Celluloid layer. For the attachment of the Celluloid layer 2, the hard rubber member 1 is provided with a rough surface which assures improved adhesion. In

2

order to attach the cushioning layer 3 to the Celluloid layer 2, the latter is softened so that it becomes sticky.

When using fibrous material for the cushioning layer, the softened Celluloid will partly penetrate into the layer 3. If rubber is used as a cushioning layer, a roughening of the rubber layer is to be recommended. As may be seen from Figs. 2 and 3, the heel lift presents a substantially spherical curvature. This curvature is produced by the Celluloid layer 2, which undergoes considerable shrinkage during its setting process, thus deforming the hard rubber member. When the heel lift is attached to the heel of the shoe, the curvature is removed. This has the effect, that the spherical zone of the heel lift is pressed against the heel with an especially strong contact pressure.

The heel piece shown in Fig. 4 is composed in the same manner as the heel lift according to Figs. 1 to 3. The only difference resides in the fact, that in the embodiment shown in Fig. 4 the cushioning layer 3, while completely covering the Celluloid layer, is affixed to the Celluloid layer only along a peripheral zone 4. The inner limit of the peripheral attachment zone is indicated by a broken line.

The composition of the heel lift according to Fig. 5 also corresponds essentially to the embodiment according to Figs. 1 to 3. In this case, however, the cushioning layer 5 is formed as a welt, so that the Celluloid layer remains uncovered in its central area.

The manufacture of the heel lift (Figure 5) having a cushioning layer in the form of a welt is rendered more complicated in comparison with the other embodiments, due to the fact that the cushioning welt has to be separately cut out by punching or has to be formed in another manner, and must subsequently be attached to the Celluloid layer. This disadvantage is, however, largely compensated by the fact, that this embodiment combines in an ideal manner the desirable features forming the object of the invention, since the Celluloid layer is covered only in a peripheral zone, the drying and curving process is not impeded, and the curvature may therefore be obtained without any additional pressure.

I claim:

1. A heel lift comprising a spherically curved base body of hard rubber, a layer of Celluloid on the upper face of the body, and a thin layer of soft, non-brittle material on the Celluloid layer.
2. A heel lift according to claim 1 in which the thin layer of non-brittle material is on the peripheral regions only of the Celluloid layer.
3. A heel lift according to claim 1 in which the thin layer of non-brittle material is a fibrous material.
4. A heel lift according to claim 1 in which the thin layer of non-brittle material is of leather.
5. A heel lift according to claim 1 in which the thin layer of non-brittle material is of rubber.
6. A heel lift comprising a spherically curved base body of hard rubber, a layer of Celluloid on the upper face of the body, and a thin layer of soft, non-brittle fibrous material on the peripheral regions of the upper surface of the Celluloid layer.
